Fig. 5

FIGURE 1 is a side view of the space condition responsive instrument embodying my new design as seen from the left;

FIGURE 2 is a front view;

FIGURE 3 is a rear view;

FIGURE 4 is a top view; and

FIGURE 5 is a front view of FIGURE 2 looking perpendicular to the plane of the circular portion as shown in FIGURE 1.

The essential features of my disclosed design reside in the portions shown in full lines in the drawing.

The undisclosed side of the space condition responsive instrument is substantially the same in appearance as the side shown.

I claim:

The ornamental design for a space condition responsive instrument, substantially as shown and described.
